SHOE PRESS LAST

Cullen L. Huntoon, St. Louis, Mo., assignor to
 Landis Machine Company, St. Louis, Mo., a corporation of Missouri

Application June 13, 1942, Serial No. 446,887

13 Claims. (Cl. 12—123)

The invention relates to lasts such as are commonly associated with presses used in cementing a shoe sole or half sole to the shoe upper, although the invention is not limited to such use but is adapted for other last-like tyes.

The last and its use are of the same general types as described in a copending application by the present inventor, Serial No. 388,209, filed April 12, 1941, and has the same general objects as the device disclosed in that application; namely, to equalize the pressure throughout the length of the shoe parts contacted by the last and to render the last adjustable to different variations in the angle between the shoe sole and shank, and preferably to render the adjustment 15 effective automatically upon the application of thrust to the last parts. The invention is particularly adaptable for use in shoe repair shops because it avoids the necessity of providing a multitude of lasts for working effectively upon shoes with different heights of heels and correspondingly different angles between the shoe sole and shank.

A further object of the present invention is to insure a more continuous and smoother contact 25 between the sole and shank engaging portions of the last without detracting from the automatic adjustment and other advantages of the last previously disclosed.

An additional object is to prevent marring of 30 the sock lining or other last opposing surface of the shoe when the last parts are slid along each other to adjust the last to the shoe.

In the accompanying drawing illustrating the present invention—

Figure 1 is a side elevation, sectioned in part, of a shoe press, including a cushion, the novel last disclosed herein, and means for thrusting the last towards the cushion, the same being illustrated as functioning to cement a shoe sole in 40 position.

Figure 2 is an enlarged side elevation and longitudinal section through the adjustable last.

Figure 3 is a top view of the shoe sole and shoe shank engaging portions of the last with the adjacent part of the thrust transmitting member of the last indicated in broken lines.

Figures 4 and 5 are detail sections taken on the corresponding section lines of Figure 2.

Figure 6 is a detail longitudinal section showing 50 portions of the parts moved to a different position than that indicated in Figure 2.

Figure 7 is a detail longitudinal section showing a modification of one feature of the structure.

The shoe press is detailed and claimed in Pat- 55

ent No. 2,268,874, issued to the present inventor January 6, 1942, and includes a base 1 and a hand wheel 2 with a shaft (not shown) journaled in the base and geared to a crank shaft 3 with pins 5 4 connected by rods 5 to a yoke 6 having a bayonet slot type of connection to receive a tongue 7 on the forward end of the upper arm of the thrust member 8 of the last which is inserted in the shoe. Base 1 mounts a pan-like support 9 into 10 which is inserted a deformable cushion 10 upon which the bottom of the shoe may rest. Rotation of hand wheel 2 moves rods 5 downwardly to apply pressure through the last to the interior of the bottom of the shoe and thrust the exterior of the bottom of the shoe against the deformable cushion 10.

Member 8 includes a foot-shaped body 11. Member 8 is rigid throughout and may consist of a single casting. Associated with the thrust transmitting member is a shoe sole engaging part 12 and a shoe shank engaging part 13, these parts being hinged to each other as best shown in Figures 3 and 4, a projecting tongue 14 on part 13 being received in an aperture 15 in part 12, the outer boundary of the aperture forming a hinge pin 16 about which tongue 14 is curved.

The thrust member and sole engaging part 12 are detachably held in assembly with each other by a pin 20 having a head 21 engaging an upwardly facing surface of the body 11 of the thrust member. Pin 20 has a portion 22 of reduced diameter extending into a recess 23 opening upwardly from the bottom of part 12. The shoulder on the pin formed by its reduced diameter portion 22 rests on top of the boss 19 surrounding recess 23. A spring 24 is seated against the inner end of recess 23 and engages a collar 25 on the lower end of the pin 20. Member body 11 is slotted, as indicated at 26, to receive pin 20 through the forward end of the body. The underside of body 11 is recessed at 27 to receive an upwardly projecting lug 28 on part 13, the bottom of the recess forming a cam coating with the upper edge of lug 28 to determine the angular relation between parts 12 and 13. The thrust member 8—11 is bored to receive a coil spring 29 secured at its upper end by detachable pin 30 and having its lower end attached to lug 28. This spring pulls part 13 up against part 11 avoiding a too loose pivotal movement of parts 13 and 12 and yieldingly holding lug 28 in groove 27 and thereby preventing lateral pivoting of part 8—11 about pin 20. The opposing faces of member 11 and part 12 are curved, and these elements are slidable over each other longitudinally of the

last to different assembly positions, two of which are indicated by the solid and broken lines showing the thrust member in Figure 2.

With the last parts assembled in the full line position indicated in Figure 2, the operator may grasp member 8 and insert the forward end of part 12 into a shoe. If the shoe has a low heel and its shank and sole are inclined to each other about as indicated in the full line position of part 13 as shown in Figure 2, these parts will be seated against the inner face of the shoe sole and shank and, upon attaching the shank to yoke 6 (Figure 1) and applying pressure in the direction of the arrow B, corresponding to the pull on yoke 6 exerted by links 5, the friction between body 11 and part 12 will hold these parts in the position indicated and the thrust will be transmitted to part 13 through its cam lug 28. If the shoe has a high heel, the workman, in inserting the last into the shoe, applies pressure in the direction of arrow A, causing body 11 to slide along the upper face of part 12 towards the broken line position indicated at 11a, the deeper portion of cam recess 27 accommodating the upward movement of part 13 towards the broken line position indicated at 13a and detailed in Figure 6. Hence parts 12 and 13 and the overlying body 11 automatically adjust themselves to any desired inclination of the shoe sole and shank without requiring a preliminary selective manual adjustment of the parts, as has been customary with previous devices for the same general purpose. Irrespective of the point at which the downward movement is limited by the resistance of the shoe shank, there will be provided a fairly smooth, continuous sole and shank engaging surface, and the shoe material will not be scratched or otherwise marred by movement of the thrust transmitting member longitudinally of the shoe engaging parts.

A bumper spring 31 has one end received in a recess in bdy 11 and has its other end positioned to abut pin 20, and this spring thrusts parts 11 and 12 to the full line position indicated in Figure 2 when the device is not in a shoe or otherwise held in a different position, rendering it unnecessary for the workman, when he picks up the last to insert it in a shoe, to move the parts from the position indicated by the broken lines 11a and 13a to the position indicated by the full lines.

The different relative positions of the three parts of the last adapt the latter to accommodate different angles between shoe soles and shanks so that substantially uniform pressure may be applied throughout the length of the shoe sole and shank of any shoe into which the last may be inserted. Obviously, complete equipment would require several lasts of different widths and lengths for extreme variations in shoes, but nevertheless each last will be adapted for a large variety of shoe styles.

Figure 7 illustrates a modification in which the yielding thrust of the shank engaging part 43 against the pressure member body 41 is effected by a compression spring 49 with its ends received in opposing recesses in shank engaging part 43 and sole engaging part 42. The spring extends beneath hinge pin 46 and the hinge lug 44 on part 43 is bifurcated to straddle spring 49. This arrangement may be preferred, particularly if it is desired, in successive operations, to frequently switch thrust transmitting member 8 to different sizes of sole and shank parts.

The details of the structure and the particular manner in which it is used may be varied from the above description without departing from the

spirit of the invention, and the exclusive use of such modifications as come within the scope of the claims is contemplated.

What is claimed is:

- 5 1. In a last for a shoe press or the like, a sole contacting part, a shank contacting part movably secured thereto, and a rigid member for applying thrust to both of said parts and movable to different positions relative to said parts and to vary the angle between said parts in a direction transversely of the general plane of the sole to which the last is applied.
- 10 2. Structure as described in claim 1 in which the thrust applying member is detachably secured to one of the parts and has a portion opposing the other of the parts, there being means yieldingly moving the latter-mentioned part into contact with said portion.
- 15 3. In a last for a shoe press or the like, a sole contacting part, a shank contacting part, said parts being arranged end to end and hinged to each other, there being recesses in their opposing ends, a coil spring with its ends seated in said recesses and extending at one side of the hinge pivot to move the parts relative to each other in one direction, a member for applying thrust to said parts in the opposite direction and movable to different positions relative to said parts and to vary the angular relation between said parts.
- 20 4. In a last for a shoe press or the like, a sole contacting part, an extension movably secured to said part to contact the shoe shank, a member through which thrust may be applied to said part and extension, said member being arranged to be assembled in different positions relative to said part and extension and automatically varying the angle between said part and extension as it moves to different positions relative thereto, the structure including means frictionally holding said member, part and extension in different assembled positions.
- 25 5. In a last for a shoe press or the like, a shoe sole contacting part, a part pivoted thereto and extending therefrom and forming an extension thereof adapted to contact a shoe shank, and a thrust transmitting member having a portion slidably assembled with one of said parts and having a portion arranged to abut the other of said parts, the contact between said member and the part with which it is assembled being curved whereby said parts are held at different angles to each other as said member is slid along the part with which it is assembled.
- 30 6. Structure as described in claim 5 which includes means yieldingly moving the parts relative to each other in one direction.
- 35 7. In a last for a shoe press or the like, a shoe sole contacting part and an extension for contacting a shoe shank, said part and extension being movable angularly relative to each other to accommodate different angular arrangements of shoe sole and shank, and a thrust transmitting member slidably assembled with said sole contacting part and having a portion opposing said shank contacting part for limiting its angular movement in one direction relative to the sole contacting part, the angle between said part and extension varying with the relative position of said member and part.
- 40 8. In a last for a shoe press or the like, a sole contacting part, a shank contacting part, said parts being arranged end to end and hinged to each other, a member overlying said parts and adapted to apply pressure to said parts to thrust the parts against the inner face of a shoe sole
- 45 75

and shank, the opposing portions of said member and one of said parts forming cam and follower elements, whereby shifting of the member longitudinally of the parts varies the inclination of the parts to each other.

9. Structure as described in claim 8 which includes a spring attached to the shank engaging part and to the overlying member and yieldingly pulling the shank engaging part and the overlying member towards each other and maintaining the contact of the cam and follower elements.

10. Structure as described in claim 8 which includes yielding means thrusting the sole engaging part and the overlying member to a relative position in which the shoe sole and shank engaging parts are at one extreme of their relative inclination.

11. Structure as described in claim 8 in which the cam and follower elements hold the shoe shank engaging part and the overlying member against relative movement transversely of the last.

12. An adjustable last for a shoe press or the

like comprising a sole engaging part and a shank engaging part pivoted to each other to swing transversely of the general plane of the sole to which the last is applied, and a thrust transmitting member slidable on one of said parts longitudinally of the last and having a portion abutting the other of said parts to limit pivotal movement of the latter transversely of said plane away from the adjacent portion of the shoe, said

5 member and parts being provided with means holding the member against disassembly from the other parts and holding the member and other parts against relative movement transversely of the last.

10 13. Structure as described in claim 12 in which the holding means comprises a slot in the thrust transmitting member and extending longitudinally of the last over the parts, there being an element on each part extending into said slot, 15 one of said elements having a head-like portion 20 engaging an upwardly facing surface of the member.
